Patented Oct. 27, 1914.

UNITED STATES PATENT OFFICE.

ANTHONY F. NUGENT, OF NEW YORK, N. Y.

FASTENING.

1,115,237.

Specification of Letters Patent. Patented Oct. 27, 1914.

Application filed April 20, 1914. Serial No. 833,191.

To all whom it may concern:

Be it known that I, ANTHONY F. NUGENT, a citizen of the United States, and a resident of the city of New York, borough of Manhattan, in the county and State of New York, have invented a new and Improved Fastening, of which the following is a full, clear, and exact description.

The invention relates to fastenings for use on house and sidewalk awnings, canopies, tents, vehicle covers, curtains and similar devices.

The object of the invention is to provide a new and improved fastening for convenient attachment to the fabric covering and for securely holding the same in place on its framework or other support and without the use of staples, rings, grommets, hooks, straps and buckles, snap hooks, lacings, tying bands and the like, thus allowing the workmen to securely fasten the fabric coverings in place, especially in extremely cold weather.

In order to accomplish the desired result, use is made of a carrier slidably engaging the side edge of the fabric covering, and means for removably fastening the carrier to the support of the awning or the like.

A practical embodiment of the invention is represented in the accompanying drawings forming a part of this specification, in which similar characters of reference indicate corresponding parts in all the views.

Figure 1 is a cross section of the fastening as applied for fastening the lower edge of the roof of a side awning to the awning frame and supporting the upper edge of the awning side; Fig. 1^a is a like view of the awning fastening as applied for fastening the lower edge of the awning side to the sidewalk; Fig. 2 is a plan view of the carrier with the key in position for supporting an awning side; Fig. 3 is a front view of the carrier with the key removed; Fig. 4 is a perspective view of the key; Fig. 5 is a reduced side elevation of the awning fastening as applied to a sidewalk awning, parts of the fabric roof being broken out; and Fig. 6 is a perspective view of one of the fasteners for attaching the end flap of the awning to the side of a building.

The sidewalk awning on which the fastening is shown applied consists of the usual skeleton frame and a fabric covering stretched over the said frame and attached thereto by the fastening hereinafter more

fully described. The skeleton frame is formed of posts A, horizontally extending side bars B and angular roof bars C carrying a ridge pole D, and the fabric covering is formed of a peak-shaped roof section E, and a section F, one on each side, as will be readily understood by reference to Figs. 1 and 5. The under side of the roof section E is provided near each side edge with a short flap or flange E' terminating in a hem E² filled with a rope or similar filling E³ so as to thicken the free edge of the flap E', as plainly indicated in Fig. 1. The thickened edge formed of the hem E² and its filling E³ is slidably engaged by a carrier G provided on its top with a retaining groove or slot G', of keyhole shape, for receiving the thickened edge of the flap E', as plainly indicated in Fig. 1. A number of carriers G are provided for each flap E' and the said carriers are spaced a few feet apart throughout the length of the side flap E' and its roof section E, as indicated in Fig. 5. Each carrier G is adapted to rest on the top of the side bar B and is provided at its under side with a cut-out portion G² through which extends a screw H screwing in one side of the carrier G, and the said screw H engages an end link of a chain I adapted to be passed around the side bar B and hooked onto a split or double hook G³ formed on the rear of the carrier G so as to securely hold the carrier G in position on the side bar B. It will be noticed that by the use of the chain I the carrier G can be readily fastened in position on the side bar B or unfastened from the same.

The front of the carrier G is provided with a socket G⁴ having an entrance G⁵ elongated in a longitudinal direction, as plainly indicated in Fig. 5. The socket G⁴ is adapted to be engaged by a key J having a shank J' terminating in an inner head J² corresponding approximately to the entrance opening G⁵ to permit of passing the head J² through the said opening, after which the key is given a quarter turn to move the head J² into a right-angled position relatively to the entrance opening G⁵ to hold the key J in position in the socket G⁴. The rear portion of the shank J' adjacent the rear head J² is preferably made square while the forward portion is made round, as indicated in Fig. 1. By this arrangement the key J is pushed inward a distance sufficient to engage the round por-

tion with the entrance opening G^5 to allow of giving the key a quarter turn, as previously explained, after which the key is pulled outward so as to engage the square portion of the shank with the entrance opening G^5 to hold the key J against accidental turning in the socket G^4 . The outer head J^2 is provided with a retaining groove or slot J^4 of keyhole shape and adapted to receive the thickened upper edge of the fabric side F of the awning, and which thickened edge is formed by providing the upper edge with a hem F' filled with rope or other filling F^2 , the same as the thickened edge of the flap E' previously described. It is understood that the head J^2 stands at a right angle to the groove J^4 so that when the key J is in engagement with the socket G^4 the head J^2 is in vertical position while the groove J^4 extends horizontally to properly support the awning side F . It will be noticed that by the arrangement described the fabric side F is properly supported by keys J and the latter are removably engaged with the sockets G^4 of the carriers G . By the construction described the carriers G by having the grooves G' can be readily slipped onto the thickened edge of the flap E' and then the carriers G can be readily fastened in place on the side bar B of the skeleton awning frame. It will also be noticed that by providing the keys J with the slots J^4 the keys can be readily slipped onto the thickened upper edge of the corresponding awning side F and the keys can be readily engaged with the sockets G^4 to support the keys and consequently the awning side F from the carriers G .

In order to fasten the lower edge of each fabric side F to the sidewalk, use is made of a carrier G , such as above described, and the lower edge of each fabric side is provided with a hem F^3 containing a filling rope F^4 , and this lower thickened edge of the side F is engaged by the groove G' of the carrier G . The chain I is provided with a slideable hook I' adapted to be hooked onto an eye I^2 let into the sidewalk, as plainly indicated in Fig. 1^a. The loose end of the chain I is hooked onto the hook G^3 of the carrier G to hold the parts in place. It will be noticed that the carriers G can be readily slipped in place on the lower thickened edge of the fabric side F until the carriers are directly above the permanent eyes I^2 in the sidewalk, and then the hooks I' can be readily engaged with the said eyes I^2 and the chain I hooked onto the hooks G^3 to securely hold the lower edge of the fabric side in place. It will be noticed that the chain I compensates for the different distances the lower edge of the fabric side F is from the surface of the sidewalk.

From the foregoing it will be seen that the several parts can be readily placed in

position to securely hold the awning roof in position on the skeleton frame, to properly support the sides of the awning from the carriers by the use of the keys J and to hold the lower edges of the sides in place. By the use of the carriers G and the keys J , the operator is not required to resort to tying the covering parts in place, it being understood that in cold weather such tying operations have to be carried on with numb fingers and require a large amount of time.

In order to fasten an end flap K to a projecting part L of the building, use is made of keys J each held slideable in the thickened edge K' of the flap K and engaging a socket O in the head O' of a screw O^2 , screwing in the part L of the building, as indicated in Fig. 6. The socket O is like the socket G^4 in the carrier G to allow the use of the same keys J on a carrier or screw.

By the arrangement described the workman is not required to sew rings, snap hooks and the like onto the fabric coverings or to rivet straps and buckles on the same or to provide the coverings with grommets.

It will be noticed that the carriers can be easily slipped in place along the thickened edges of the fabric coverings and fastened in place by the use of the chains.

Although I have shown and described the fastening applied to a sidewalk awning it is expressly understood that the fastening can be used on any kind of covering or canopy, or on tents, vehicle coverings and the like.

Having thus described my invention, I claim as new and desire to secure by Letters Patent:

1. A fastening for the fabric covering of awnings, tents and the like, comprising a carrier having a retaining groove for slidably engaging the thickened edge of the fabric covering for the awning, tent or the like, a hook on the said carrier, and a chain attached at one end to the said carrier and adapted to engage the said hook.

2. A fastening for the fabric covering of awnings, tents and the like, comprising a carrier having a retaining groove for slidably engagement with the thickened edge of one member of the fabric covering, a hook on the carrier, a chain attached at one end to the said carrier and adapted to engage the said hook, a socket on the said carrier, and a key adapted to engage the said socket and having a head provided with a retaining groove for slideable engagement with the thickened edge of another covering member.

3. In combination, an awning frame, a fabric awning roof having its side edge thickened, a fabric awning side having its upper edge thickened, a carrier slidably engaging the said side edge of the awning roof, means for removably fastening the carrier to the awning frame, and means slidably engaging the said upper edge of an

- awning side and removably engaging the said carrier.
4. A fastening for the fabric covering of an awning and the like, comprising a carrier having a slot for engagement with the enlarged edge of one part of the awning, and a key removably engaging the said carrier and having a slot for engagement with the enlarged edge of another part of the awning.
5. A fastening for the fabric covering of an awning and the like, comprising a carrier having a slot for engagement with the enlarged edge of one part of the awning, a key removably engaging the said carrier and having a slot for engagement with the enlarged edge of another part of the awning, and means for detachably fastening the said carrier to the support of the awning.
6. A fastening for the fabric covering of an awning and the like, comprising a carrier, fastening means for fastening the carrier to the support of the awning, the carrier having a slot for the reception of the hem of the roof flap of the awning and the said carrier having a socket and a key for removable engagement with the said socket and having a slot for the reception of the upper end of the awning side to support the latter.
7. A fastening for the covering of an awning and the like, comprising a carrier having a hook at the inner side and a slot at the top for the reception of the enlarged
- edge of the tying flap of the awning roof, the said carrier being provided at the front with a socket, a chain attached at one end to the said carrier and adapted to pass around the awning frame and engage the said hook, and a key removably engaging the said socket and adapted to carry the awning side.
8. A fastening for the covering of an awning and the like, comprising a carrier having a slot at the top, a socket at the front and a hook at the rear, a chain attached at one end to the under side of the said carrier and adapted to pass around a member of the awning support to then engage the said hook to fasten the carrier in place on the said frame member, and a key adapted to engage the said socket and having a slot for the reception of a thickened upper edge of a side of the awning.
9. A fastening for fastening a fabric covering to a support, comprising a fixed member having a head provided with a socket, and a key adapted to engage the said socket and having a head provided with a retaining groove adapted to slidingly engage the thickened edge of the said fabric covering.
- In testimony whereof I have signed my name to this specification in the presence of two subscribing witnesses.
- ANTHONY F. NUGENT.
- Witnesses:
- THEO. G. HOSTER,
PHILIP D. ROLLHAUS.
